PICKER MECHANISM

Charles H. Oslund, Worcester, Mass.

Application April 16, 1940, Serial No. 329,936

15 Claims. (Cl. 216—54)

This invention relates to picker mechanisms, and more particularly to a mechanism forming a part of a labeling machine and arranged to transfer labels from a label holder and place them in contact with the articles to be labeled.

My invention is well adapted for use in a labeling machine of the rotary type, which comprises a rotary table on which the articles, such as glass bottles, are supported during the labeling operation. In machines of this type, it is customary to employ a pair of spaced substantially parallel picker blades which are first coated with adhesive and then moved into contact with the labels in a label holder to remove a set of labels therefrom. The pickers are then moved to a position in front of the article, and a label gripper is brought into contact with the central portions of the labels to hold them against the article, whereupon the pickers are withdrawn and the cycle is repeated for the next article. In so-called "duplex" machines it is the practice to employ two sets of pickers which transfer labels to alternate articles on the table. Some machines are provided with mechanism for swiveling the picker blades to allow the articles to pass between them.

Since labeling machines are often operated at high speeds, it is important to decrease the distance traveled by the picker blades, if possible, in order to reduce their speed and avoid shock and wear on the driving mechanism. It is also important to avoid applying the adhesive to the picker blades while they are positioned above the table, as otherwise the table and articles will become spattered with adhesive. Interruptions in the movement of the pickers for the application of adhesive thereto are undesirable, since they necessitate higher operating speeds during other parts of the cycle.

It is one object of the invention to provide a simple and inexpensive picker mechanism so arranged that the pickers will have a comparatively short path of travel.

It is a further object of the invention to provide a picker mechanism particularly adapted for use with duplex labeling machines and so constructed as to simplify the various parts and reduce the number of cams required.

It is a further object of the invention to provide a picker mechanism of a simple and dependable construction having blades between which the articles may pass without requiring driving mechanism to separate the blades.

It is a further object of the invention to provide a picker mechanism having picker blades

to which adhesive is applied without interrupting the movement of the blades and while the blades are so located as to avoid spattering of adhesive on the articles to be labeled.

5 With these and other objects in view, as will be apparent to those skilled in the art, the invention resides in the combination of parts set forth in the specification and covered by the claims appended hereto.

10 Referring to the drawings illustrating one embodiment of the invention, and in which like reference numerals indicate like parts,

Fig. 1 is a top plan view of a labeling machine;

Fig. 2 is an elevation of the machine viewed in the direction of the arrow 2 in Fig. 1;

Fig. 3 is an elevation of the machine viewed in the direction of the arrow 3 in Fig. 1;

Fig. 4 is a section on the line 4—4 of Fig. 3;

Fig. 5 is a section on the line 5—5 of Fig. 3;

20 Fig. 6 is an elevation of the picker blades positioned in front of a bottle;

Fig. 7 is a fragmentary plan view, with the picker blades shown in section on the line 7—7 of Fig. 3;

25 Fig. 8 is a view similar to Fig. 7 showing one bottle passing between two of the picker blades; and

Fig. 9 is a view similar to Fig. 7 showing the picker blades after the bottle has passed the same, and indicating their subsequent positions in broken lines.

The embodiment illustrated comprises a circular horizontal table 15 arranged to be rotated about a vertical axis by any suitable and well-known means and to support the articles to be labeled, such as glass bottles. The bottles are placed upon the table in single file by feeding mechanism of any suitable type, and after they have traveled through somewhat less than one

30 revolution they are removed from the table by a suitable transfer mechanism. The table rotates in a clockwise direction as viewed in Fig. 1. Associated with the table are bottle locating brackets 16 which engage the rear surfaces of the

35 bottles close to the table, vertically reciprocable clamps 17 which engage the tops of the bottles to hold them firmly against the table, and label grippers 18 which extend upwardly through arcuate slots 19 in the table and move along these slots to hold the labels against the bottles. These parts are of well-known construction and hence require no further description.

The present invention provides a picker mechanism which serves to place labels against the front surfaces of the bottles, whereupon the label

grippers 18 move into engagement with the labels. In the particular embodiment of the invention illustrated, the picker mechanism is of the duplex type, and the construction is such that labels are applied to two consecutive bottles simultaneously. This has a number of advantages which will become apparent as the description proceeds.

My improved picker mechanism comprises two pairs of picker blades 20, the blades in each pair being spaced apart and substantially parallel. These blades are arranged to move simultaneously into positions in front of two of the bottles and substantially radially of the table 15, as shown particularly in Fig. 7, with the labels adhering to the front surfaces of the blades. The blades are preferably slightly inclined from the vertical, with their lower ends somewhat in advance of their upper ends, as shown in Fig. 3. In this latter figure, the picker blades 20 and label grippers 18 are shown as viewed in radial directions for simplicity of illustration.

The blades 20 of each pair are necessarily somewhat closely spaced, particularly in case relatively short labels are to be applied, and it will ordinarily be necessary to move the blades apart to allow the passage of the bottles between them. In the preferred construction this separation of the blades is brought about by the camming action of the bottles themselves, no separate driving mechanism being required for the purpose. As illustrated, each blade 20 is fastened at its upper end to an L-shaped member 21 (Fig. 6) which is pivotally secured by means of a horizontal pin 22 to a supporting bracket 24, there being one of these brackets 24 for each pair of pickers. A coiled tension spring 25 connects the depending portions of the members 21 to swing the picker blades toward one another, this movement being limited by vertical set screws 26 mounted in the inwardly extending portions of the members 21 and engaging the bracket 24. With this construction the forwardly moving bottles will cam the picker blades apart, as shown in Fig. 8, and the labels will be carried along by the bottles. The springs 25 will return the blades to their original positions as soon as the bottles have passed between them.

Immediately after the bottles and the clamps 17 have left the picker blades, each pair of blades is turned about a separate vertical axis until the operative or label-engaging surfaces of all the blades are located in a common plane and face outwardly away from the table. This turning movement takes place in a direction opposite to the rotation of the table 15, i. e. in case of clockwise table rotation as illustrated the picker blades will be turned counterclockwise. Because of the original radial positioning of the blades, the forward pair of blades will need to be turned through an angle slightly greater than ninety degrees, as indicated by the broken lines in Fig. 9, whereas the rearward pair of blades will need to be turned through an angle slightly less than ninety degrees. The vertical axes about which these turning movements take place are preferably located inside the periphery of the table 15 and intersect the path of the bottles. Each axis is also preferably close to the corresponding pair of blades and slightly in the rear thereof.

In order that the desired turning motion of the picker blades may be obtained, each bracket 24 is mounted on the lower end of a vertical shaft 28 (Fig. 3) and each of these shafts is rotatably supported in a bearing 29 on a horizontal frame

member 30 extending across a portion of the table 15 therebeneath and carried by two spaced upright columns 31. A gear 33 is secured to the upper portion of each shaft 28, preferably through the medium of a suitable clamping device 34 mounted on the shaft above the gear and provided with opposed screws 35 which engage a lug 36, projecting upwardly from the gear, whereby the gear can be angularly adjusted about the shaft as desired. Each gear 33 is oscillated by means of a gear segment meshing therewith, the gear segment 38 which is associated with the forward pickers having a somewhat greater pitch radius than the gear segment 39 which is associated with the rear pickers, since the latter require a smaller angle of oscillation. The gear segments 38 and 39 are adjustably bolted to members 40 and 41 respectively, each of which is pivotally mounted on a vertical pin 43 carried by the frame member 30. Each of the members 40 and 41 is provided with a cam roller 44 (Fig. 1) which engages a cam 45 mounted on the upper end of a vertical shaft 46. Each shaft 46 is rotatably supported in an upper bearing 48 on the frame member 30 and in a lower bearing 49 on the adjacent column 31. On the lower end of each shaft 46 there is mounted a bevel gear 50, and these gears are driven by bevel gears 51 carried by a horizontal shaft 53 which is rotatably supported in suitable bearings 54 on the columns 31, as shown particularly in Fig. 3. The gears 50 and 51 are of equal size, so that the shafts 53 and 46 rotate at the same speed. The horizontal shaft 53 is driven in timed relation to the table 15 so that the shaft will make one revolution for each pair of bottles which passes through the machines. For example, if the table 15 is provided with eight bottle stations, the shaft 53 will rotate at exactly four times the speed of the table.

After the bottles have passed between the picker blades 20, and the latter have started their turning movement under the influence of the cams 45 and associated mechanism to bring their operative surfaces into a common plane, they are swung outwardly and upwardly away from the table 15 and into contact with the labels in label holders 56 (Fig. 2). This swinging movement takes place about horizontal axes located near the upper ends of the pickers. In the preferred construction illustrated each bracket 24 is pivotally connected by means of a horizontal pin 58 (Fig. 3) to an offset arm 59 which extends downwardly from the lower portion of the adjacent vertical shaft 28. The pins 58 are parallel with the operative surfaces of the picker blades. Each bracket 24 is formed with a pair of spaced upwardly extending ears 60 which are pivotally connected by means of aligned horizontal pins 61 (Fig. 5) to a ring 62. This ring is located between two vertically spaced flanges 64 on the lower end of a vertical rod 65 which is slidable through the center of the adjacent shaft 28, the latter being axially bored to receive the rod. The aperture in the center of the ring 62 is of sufficient size to allow the slight lateral movement required as the bracket 24 oscillates about the pin 58.

Means is provided to reciprocate the rods 65 and thereby swing the picker blades to and from the label holder. For this purpose a horizontal rod 67 extends parallel with the shaft 53 and is suitably supported at its ends by brackets 68 (Fig. 2) carried by the columns 31. This rod supports a sleeve 69 (Figs. 3 and 4) having a projecting arm 71 which carries a cam roller 72. This cam roller engages a cam 73 mounted on the

horizontal shaft 53. The sleeve 69 is also provided with two projecting arms 75 located near its ends and connected by vertical links 76 to vertical rods 77 which are slidably supported in bearings 78 on the frame member 30. As shown in Fig. 1, the oscillating members 40 and 41 are provided with apertures 80 to clear the bearings 78. Each rod 77 is connected to the adjacent rod 65 to reciprocate the same, and this is preferably brought about by a mechanism arranged to minimize the possibility of excessive friction. As shown particularly in Figs. 1 and 3, each rod 77 carries a hub 82 thereon having a horizontally projecting boss 83 which is bored to receive a bar 84 projecting horizontally from a hub 85 carried by the adjacent rod 65. Thus, if the rods 77 and 65 are not exactly parallel, the bar 84 will slide slightly within the boss 83 and prevent the parts from binding.

Adhesive is applied to the operative surfaces of the picker blades during their outward and upward swinging movement, and preferably without interrupting or delaying such movement. For this purpose there is provided a pair of horizontally aligned gum rolls 87 (Figs. 1 and 2) each of which is mounted on the lower end of an arm 88 pivotally secured at its upper end to a bracket 89. These rolls are parallel with the shaft 53, and they are arranged to swing through a circular arc directly beneath the label holders. At the lower end of their swinging movement the rolls 87 engage the roll 90 of the usual gum box 91. In order to actuate the gum rolls 87, there is provided a horizontal rod 93 (Figs. 2, 3 and 4) parallel with the shaft 53 and supported at its ends in the frame columns 31. This rod supports a sleeve 94 having a projecting arm 95 which carries a cam roller 96. This cam roller engages a cam 97 mounted on the horizontal shaft 53. The sleeve 94 is also provided with two projecting arms 98 located near its ends and connected by vertical links 99 to the gum roll arms 88.

The operation of the invention will now be apparent from the above disclosure. The shaft 53 and the table 15 will be rotated in timed relationship by a suitable source of power, and bottles will be supplied to the table and removed therefrom by suitable mechanism. As the bottles approach the picker blades 20, the latter will be in the substantially radial positions shown in Fig. 7, and the corresponding label grippers 18 will move into contact with the central portions of the labels to hold them against the bottles. As the bottles advance they will swing the pickers apart about the pins 22, allowing the bottles to pass between the pickers and strip the labels therefrom. The springs 25 will restore the pickers to their original positions. As soon as the clamps 17 have cleared the pickers, the continued rotation of the cams 45 will transmit motion through the gear segments 33 and 39 to the gears 33 and turn the shafts 28 in a counter-clockwise direction until the operative surfaces of the pickers are in a common plane. At this time the pins 58 will be in alignment. During the turning movement of the pickers, the continued rotation of the cam 97 will swing the gum rolls 87 upwardly to the top of their arc of travel. The cam 73 will function to lower the rods 77 and 65, and, through the swivel connection afforded by the pins 61, the brackets 24 and the picker blades 20 will be swung about the pins 58. Preferably this swinging motion begins somewhat before the completion of the turning motion, the two motions thus overlapping. Immediately after the turning motion has ceased,

the continued swinging motion will bring the operative surfaces of the blades, which are now in a common plane, into engagement with the gum rolls 87, and the latter will travel downwardly along the pickers under the influence of the cam 97, applying adhesive to the pickers during their outward travel without interrupting the same. As the gum rolls leave the lower ends of the pickers and return to the roll 90 for a new supply of adhesive, the pickers will engage a set of labels in the holders 56 and immediately swing downwardly again about the pins 58. As the pickers approach the table 15 they will be turned in a clockwise direction by the action of the cams 45 and again assume radial positions in front of the next pair of bottles, thus completing one operating cycle.

It will be noted that although this is a duplex machine, which labels two bottles in each cycle, nevertheless only four cams are required for the operation of the entire picker mechanism, including the gum rolls. This greatly reduces the cost of manufacture. The label holders 56 are located close to the table, so that the path of travel of the pickers is comparatively short. The adhesive is applied to the pickers while they are swinging outwardly, and spattering of adhesive on the table and bottles is avoided. The picker blades are separated by the camming action of the bottles themselves, so that the construction is greatly simplified.

Having thus described my invention, what I claim as new and desire to secure by Letters Patent is:

1. A labeling machine comprising means to move articles to be labeled along a predetermined path, a pair of picker blades arranged to transfer a label into a position in front of one of said articles, a supporting bracket for the picker blades, the picker blades being pivotally secured at their upper ends to the bracket in such a manner that they will be swung apart substantially in the plane of their operative surfaces by the camming action of the article as it passes between them, and spring means yieldably urging the picker blades toward one another.

2. A labeling machine comprising means to move articles to be labeled along a predetermined substantially horizontal path, a label picker, means to oscillate the picker about a substantially vertical axis located closely adjacent to the said path, and means to oscillate the picker about a substantially horizontal axis in a definite relationship to its movements about the vertical axis.

3. A labeling machine comprising means to move articles to be labeled along a predetermined substantially horizontal path, a label picker, means to oscillate the picker about a substantially vertical axis which intersects the said path, and means to oscillate the picker about a substantially horizontal axis in a definite relationship to its movements about the vertical axis.

4. A labeling machine comprising a rotary table to support articles to be labeled, a label picker, means to oscillate the picker about a substantially vertical axis located close to the picker and inside the periphery of the table, and means to oscillate the picker about a substantially horizontal axis in a definite relationship to its movements about the vertical axis.

5. A labeling machine comprising a rotary table to support articles to be labeled, a substantially vertical shaft located above the path of the articles on the table, a label picker extending downwardly from the shaft, means pivotally con-

necting the picker to the shaft on a substantially horizontal axis parallel with the operative surface of the picker, means to oscillate the shaft, and means to oscillate the picker about its pivotal connection in a definite relationship to the oscillation of the shaft.

6. A labeling machine comprising a substantially vertical hollow shaft, a label picker extending downwardly therefrom, means pivotally connecting the picker to the shaft on a substantially horizontal axis, a rod extending through the shaft, means connecting the lower end of the rod to the picker so that vertical movements of the rod will cause the picker to swing about the said axis, means to oscillate the shaft, and means to reciprocate the rod in a definite relationship to the oscillations of the shaft.

7. A labeling machine comprising a substantially vertical hollow shaft, an offset arm on the lower portion of the shaft, a bracket pivotally connected to the arm on a horizontal axis, a picker blade secured to the bracket and extending downwardly therefrom, a rod extending through the shaft, means providing vertically spaced flanges on the lower portion of the rod, a ring located between the flanges, two ears projecting from the bracket on opposite sides of the ring, horizontally aligned pins connecting the ears to the ring, means to oscillate the hollow shaft, and means to reciprocate the rod in a definite relationship to the oscillations of the shaft.

8. A labeling machine comprising a substantially vertical hollow shaft, an offset arm on the lower portion of the shaft, a bracket pivotally connected to the arm on a horizontal axis, a picker blade secured to the bracket and extending downwardly therefrom, a rod extending through the shaft, means connecting the lower end of the rod to the bracket so that vertical movements of the rod will cause the picker to swing about the said axis, a gear mounted on the upper portion of the shaft, a gear segment meshing with the gear, a cam rotatable about a substantially vertical axis, means connecting the cam to the gear segment to oscillate the same, and means to reciprocate the rod in a definite relationship to the oscillations of the gear segment.

9. A labeling machine comprising a substantially vertical hollow shaft, an offset arm on the lower portion of the shaft, a bracket pivotally connected to the arm on a horizontal axis, a picker blade secured to the bracket and extending downwardly therefrom, a rod extending through the shaft, means connecting the lower end of the rod to the bracket so that vertical movements of the rod will cause the picker to swing about the said axis, a second substantially vertical rod slidably mounted adjacent to the first-mentioned rod, means connecting the upper portions of the two rods, means to oscillate the hollow shaft, and driving means connected to the lower end of the second rod to reciprocate the same in a definite relationship to the oscillations of the shaft.

10. A labeling machine comprising a rotary table to support articles to be labeled, a substantially vertical shaft located above the path of the articles, two spaced picker blades extending downwardly from the shaft, means pivotally connecting the blades to the shaft on a substantially horizontal axis parallel with the operative surfaces of the blades, the blades being located in a substantially radial position in front of an article as it approaches, a label holder located at one side of the table, means to turn the shaft in a direction opposite to the direction

of rotation of the table after the article has passed between the blades and thus cause the operative surfaces of the blades to face away from the table, means to swing the blades upwardly and outwardly about the said horizontal axis and into engagement with a label in the said holder, means to apply adhesive to the blades as they swing upwardly and outwardly, means to swing the blades with a label thereon in the opposite direction, and means to turn the shaft in the opposite direction and thus return the blades to their original positions.

11. A labeling machine comprising two pairs of picker blades, actuating means for the blades arranged to align the operative surfaces of both pairs of blades in a common plane during one portion of the operating cycle, and means to apply adhesive to the blade surfaces while they are thus aligned.

12. A labeling machine comprising means to move articles to be labeled along a predetermined path in single file, two pairs of picker blades, label holding means, means to move the picker blades to align their operative surfaces, means to apply adhesive to the blade surfaces while they are thus aligned, means to move the adhesive-coated blades into contact with labels in said holding means, and means to move the respective pairs of blades with labels thereon into positions in front of two consecutive articles.

13. A labeling machine comprising a rotary table arranged to support a series of articles to be labeled in single file, two pairs of picker blades, label holding means, means to move the picker blades to align their operative surfaces, means to apply adhesive to the blade surfaces while they are thus aligned, means to move the adhesive-coated blades into contact with labels in said holding means, and means to move the respective pairs of blades with labels thereon into substantially radial positions in front of two consecutive articles.

14. A labeling machine comprising a rotary table arranged to support a series of articles to be labeled in single file, two substantially vertical shafts above the path of the articles on the table, a pair of picker blades pivotally secured to the lower end of each shaft on a substantially horizontal axis parallel with the operative surfaces of the blades, each pair of blades being located in a substantially radial position in front of one article as it approaches, label holding means located at one side of the table, means to turn the shafts and bring the said axes into alignment, means to swing the blades upwardly and outwardly about the said axes and into engagement with labels in said holder, means to apply adhesive to the blades as they swing upwardly and outwardly, means to swing the blades with labels thereon in the opposite direction, and means to turn the shafts in the opposite direction and thus return the blades to their original positions.

15. A labeling machine comprising a rotary table arranged to support a series of articles to be labeled in single file, two substantially vertical hollow shafts above the path of the articles on the table, an offset arm on the lower end of each shaft, a pair of picker blades pivotally secured to each arm on a substantially horizontal axis parallel with the operative surfaces of the blades, each pair of blades being located in a substantially radial position in front of one article as it approaches, label holding means located at one side of the table, a vertical rod extending through each shaft, means connecting the lower ends of

the rods to the blades so that vertical movements of the rods will result in swinging movements of the blades about said axes, rotary cams connected to the shafts and arranged to turn the shafts, after the articles have passed between the blades, in a direction opposite that of the table rotation and bring the said horizontal axes into alignment, a single rotary cam connected to both said rods to actuate the same and cause the blades to swing upwardly and outwardly about their aligned axes into engagement with labels in said holding

means, two horizontally aligned gum rolls, and a single rotary cam connected to both the gum rolls and arranged to move them over the operative surfaces of the blades as they swing upwardly and outwardly, the rod-actuating cam serving to swing the blades with labels thereon downwardly toward the table, and the shaft-actuating cams serving to turn the shafts in the reverse direction and thus return the blades to their original positions.

CHARLES H. OSLUND.
